CLAIM

The ornamental design for a pitcher lid, as shown and described.

DESCRIPTION

FIG. 1 is a front top perspective view of the new design.
 FIG. 2 is a rear top perspective view of the new design, shown with the unclaimed side clips in a raised position.
 FIG. 3 is a right side view of the new design.

FIG. 4 is a left side view of the new design.

FIG. 5 is a front view of the new design.

FIG. 6 is a rear view of the new design.

FIG. 7 is a top view of the new design.

FIG. 8 is a bottom view of the new design showing the underside of the pitcher lid, which forms no part of the claimed design.

FIG. 9 is a front top perspective view of the new design, together with an unclaimed associated pitcher body illustrated in dash-dot lines.

FIG. 10 is a front top perspective view of the second embodiment of the new design;

FIG. 11 is a rear top perspective view of the second embodiment of the new design, shown with the unclaimed side clips in a raised position;

FIG. 12 is a right side view of the second embodiment of the new design;

FIG. 13 is a left side view of the second embodiment of the new design;

FIG. 14 is a front view of the second embodiment of the new design;

FIG. 15 is a rear view of the second embodiment of the new design;

FIG. 16 is a top view of the second embodiment of the new design;

FIG. 17 is a bottom view of the second embodiment of the new design showing the underside of the pitcher lid, which forms no part of the claimed design; and,

FIG. 18 is a front perspective view of the second embodiment of the new design, together with an unclaimed associated pitcher body illustrated in dash-dot lines.

The dash lines shown in the drawings illustrate portions of the pitcher lid that form no part of the claimed design. The dash-dot lines shown in FIGS. 9 and 18 illustrate environmental structure of an associated pitcher body that forms no part of the claimed design. The shading lines shown in the drawings represent the three-dimensional contour of the claimed design and are not intended to indicate surface decoration.
